CLAIM

The ornamental design for a terminal for wireless communication, as shown and described.

DESCRIPTION

FIG. 1 is a first perspective view of the front, bottom and left side a terminal for wireless communication showing our new design;

FIG. 2 is a second perspective view of the rear, top and right side view thereof;

FIG. 3 is a front view thereof;

FIG. 4 is a rear view thereof;

FIG. 5 is a left side view thereof;

FIG. 6 is a right side view thereof; and,

FIG. 7 is a top view thereof, a bottom view being a mirror image thereof.

The broken lines shown are included for the purpose of illustrating the unclaimed portions of the terminal for wireless communication and form no part of the claimed design.
